UNITED STATES PATENT OFFICE.

CHARLES FREDRICK SCHILD, OF CAMBRIDGE, OHIO.

DRYING-HANGER.

No. 853,739.

Specification of Letters Patent.

Patented May 14, 1907.

Application filed December 1, 1905. Serial No. 289,824.

To all whom it may concern:

Be it known that I, CHARLES FREDRICK SCHILD, a citizen of the United States, and a resident of Cambridge, in the county of Guernsey and State of Ohio, have invented a new and Improved Drying-Hanger, of which the following is a full, clear, and exact description.

This invention relates to improvements in hangers or brackets adapted to be attached to a wall adjacent to a range, or at any other convenient place, and upon which, towels or similar articles may be suspended for drying.

The object of the invention is to provide a device of this character that will be simple and inexpensive in construction; that may be drawn out or elongated as occasion may require, and that may be turned to any desired position.

I will describe a drying hanger embodying my invention and then point out the novel features in the appended claim.

Reference is to be had to the accompanying drawings forming a part of this specification, in which similar characters of reference indicate corresponding parts in all the figures.

Figure 1 is a side elevation of a drying hanger embodying my invention; and Fig. 2 is a section on the line $x-x$ of Fig. 1.

The drying hanger comprises a swinging member consisting of two spaced plates 1, 2, each being provided with a longitudinal slot 3. The inner ends of the plates 1 and 2 have inwardly extended portions 4 from which flanges 5 project, and secured between the flanges 5 is a downwardly extended pin 6 mounted to swing in a socket member 7 secured between vertical plates 8 which are stationarily fixed to a wall or the like, by screws or other suitable means. At the upper portion of the plate 8 is another socket member 9 for receiving a pin 10, the upper end of said pin 10 being turned slightly downward and threaded to engage with one end of a turn-buckle 11, the other end of said turn-buckle engaging with a threaded stem portion of diverging brace rods 12 connected at their lower ends respectively to the plates 1 and 2.

By means of the turn-buckle the plates may be adjusted should the pivot pins 6 and 10 or the socket members therefor become worn.

The hanger proper comprises a plurality of crossed pivotally-connected bars; the inner end bars 13 are pivoted at their adjacent ends to a pin 14 which passes through the flanges 5 and the outer ends are pivotally connected to cross-bars 15, the centers of said cross-bars 15 being mounted to swing on a pivot 16 the ends of which pass outward and are adapted to slide in the slots 3 formed in the plates 1 and 2; the said pivot 16 is headed as clearly shown in Fig. 2 and between the inner sides of the plates and the said bars 15, sleeves 17 are mounted on the pivot, which will prevent lateral movements of the bars with relation to the plates. Carried by the bars 15 is a plurality of crossed pivotally connected bars 18 which are practically in the form of toggle links and on these bars 18 are hooks 19 for suspending articles to be dried. For the purpose of giving strength to the several bars outward of the bars 13 they may be made of angle-iron.

By pivotally connecting the bars as above described, it is obvious that they may be drawn out to any desired length, and by mounting the plates 1 and 2 the whole device may be swung to any desired position and in fact may be swung closely against the wall when not in use, and when not in use the several bars may be moved into a position between the plates 1 and 2.

Having thus described my invention I claim as new and desire to secure by Letters Patent:

A drying hanger, comprising spaced plates longitudinally slotted and mounted to swing, and also having inwardly extended portions at the inner end provided with flanges, a plurality of toggle links, the inner end links being pivoted between the said flanges, and a pivot for the pair of links next to the inner end links, the said pivot being extended into said slots.

In testimony whereof I have signed my name to this specification in the presence of two subscribing witnesses.

CHARLES FREDRICK SCHILD
